(57) **CLAIM**

The ornamental design for a clip for attaching decorative accessories, as shown and described.

DESCRIPTION

FIG. 1 is an isometric view of the clip for attaching decorative accessories showing our new design, the unclaimed decorative accessory being shown connected to the back of the clip. FIG. 2 is an isometric view of the clip, the unclaimed decorative accessory being shown connected to the back of the clip and an unclaimed strap being shown as being threaded between the clip and the decorative accessory.

FIG. 3 is an isometric view of the clip, the unclaimed decorative accessory being shown connected to the back of the clip and an unclaimed portion of one side of a hook-and-loop fabric being shown connected to the front of the clip.

FIG. 4 is an enlarged back side isometric view of a second embodiment for a clip for attaching decorative accessories showing our new design.

FIG. 5 is a first side view thereof, the second side view being a mirror image thereof.

FIG. 6 is a top plan view thereof.

FIG. 7 is a bottom plan view thereof.

FIG. 8 is a front view thereof; and,

FIG. 9 is a back view thereof.

The broken-lines shown in the center of FIG. 4 and FIGS. 6-9 indicate that a specific width forms no part of the claimed design.

The phantom depictions of the band, strip, and/or decorative accessory shown in FIGS. 1-3 are included for environmental purposes and form no part of the claimed design.
